UNITED STATES PATENT OFFICE.

JENKIN P. DAVIS, OF CINCINNATI, OHIO.

MECHANICAL STOKER.

1,186,971.

Specification of Letters Patent. Patented June 13, 1916.

Application filed May 6, 1915. Serial No. 26,296.

To all whom it may concern:

Be it known that I, JENKIN P. DAVIS, a citizen of the United States of America, and resident of Cincinnati, county of Hamilton, State of Ohio, have invented certain new and useful Improvements in Mechanical Stokers, of which the following is a specification.

This invention relates to improvements in mechanical stokers and particularly to mechanical stokers of the class employing inclined agitating grates in which the fuel is delivered to the uppermost portions of the grates and is gradually worked to the lowermost portions thereof during the process of combustion.

An object of my invention is to produce a mechanical stoker adapted to create a high rate of combustion with a minimum amount of fuel.

A further object is to produce a mechanical stoker which is adapted to create more thorough combustion of the fuel and to consequently eliminate a great proportion of the smoke produced from ordinary stokers.

A further object is to produce a mechanical stoker in which a series of continuously moving fuel feeders, coking plates and grate bars are provided and mounted in such a manner that the fuel is properly distributed over the grate bars to produce greater efficiency with a materially simplified stoker construction.

These and other objects are attained in the stoker described in the following specification and illustrated in the accompanying drawings in which;

Figure 1 is a side elevation of a stoker embodying my invention, with the frame members on one side removed and certain parts shown in section to more fully illustrate the interior construction thereof. Fig. 2 is a front elevation of the stoker. Fig. 3 is a plan view of the stoker. Fig. 4 is a fragmental sectional view of a detail of the stoker. Fig. 5 is a plan view of the engine for operating the stoker.

The stoker embodying my invention consists of a frame 6 built up of two side frame members 7 and 8 connected by transversely extending channel and angle iron members 9 and 10 adjacent to the bottom of the frame, and by means of plates 11 and 12 forming a hopper 13, at the top of the frame.

Mounted on the front of the frame is a mechanism 14 from which the interior

mechanism of the stoker receives its motion, and back of the front of the stoker are located a series of coking plates 15 which extend transversely of the frame and which are adapted to discharge fuel onto a series of grate bars 16 which extend longitudinally and which are mounted at one end on the frame 6 and at their opposite end on a secondary frame 17 located at the rear of the furnace and at a lower level than the frame 6. This frame 17 consists of side members 18 and 19 connected with one another by means of the angle irons 20 and 21 extending across the back and by means of T-irons 22 and 23 extending across the top adjacent to the front of the side members. Upon this frame is located the retarding grate 24, and to the rear of the retarding grate is located the dumping grate 25.

In addition to the coking plates 15 and the grate bars 16, the frame 6 has mounted upon it a movable member 26 which is located at the bottom of the hopper 13 and which acts as a fuel feeder adapted to push the fuel from the bottom of the hopper and to discharge the fuel onto a concave plate 27 located above the coking plates 15 and adapted to act as a distributing plate for the fuel delivered from the hopper. In front of this plate is located a movable member 28 which is similar to the member 26, but which operates as a fuel pusher for the purpose of pushing the fuel from the plate 27 onto the coking plates 15. This fuel pusher operates alternately with the fuel feeder 26 and is connected with the operating mechanism 14. In addition to the connection of the fuel feeder 26 and the fuel pusher 28, the coking plates 15 which are mounted in bearings provided in the side frame members 7 and 8, are connected with the mechanism 14 by means of links 29 and 30. The grate bars 16 located to the rear of the coking plates 15 are also connected with the mechanism 14 by means of a link 31, in the same manner that the links 29 and 30 are connected therewith. The retarding grate 24 is a stationary grate and is intended to merely retard the delivery of unconsumed fuel to the dumping grate 25 for the purpose of permitting complete combustion of the fuel before it is pushed on the dumping grates, from which the fuel is discharged into the ash pit of the furnace.

In the operation of my improved stoker I provide for alternate movement of the

coking plates 15 and the grate bars 16 in addition to the alternate movement of the fuel feeder 26 and the fuel pusher 28. This alternate movement of the movable members is secured by suitable connections with the operating mechanism 14 which I will now describe.

Extending transversely of the stoker is a shaft 32 and a shaft 33, both of which are 10 adapted to receive an oscillating motion from a short shaft 34 which is connected with the engine illustrated in Fig. 5, in the following manner: The engine is preferably one of the reciprocating type in which 15 the piston rod is adapted to move backwardly and forwardly, and is connected with an arm 35 extending downwardly from the shaft 34 for the purpose of rocking the arm and the shaft as the piston rod 20 moves in and out. Connected with the shaft is an arm 36 which extends toward the front and which is connected with links 37 and 38 secured to the respective arms 39 and 40 mounted on the respective shafts 32 and 25 33. By this means the same motion communicated by the engine to the shaft 34 is communicated to the shafts 32 and 33. Mounted on the shaft 32 are a series of 30 downwardly extending arms or cranks 41 which are connected with the fuel feeder 26 for the purpose of operating the several portions thereon, the feeder being preferably constructed in several parts as illustrated in Fig. 2, for the purpose of permitting 35 adjustment of the several portions to discharge the correct amount of fuel onto the plate 27, to effect proper distribution thereof throughout its travel toward the dumping grate. This adjustable connection 40 between the portions of the feeder 26 and the crank arms 41 will be hereinafter more fully described.

Mounted on the shaft 33 at points adjacent to the opposite sides of the frame are 45 double arms 42 to which the links 29, 30 and 31, connected with the coking plates and the grate bars, are connected. In addition to the connection of the links 29, 30 and 31 with the double arm cranks 42, the fuel 50 pusher 28 is also connected therewith at the upper end of the branch 42^a of the arm. At the lower end of the arm, the link 31 which operates the alternately moving bars 16, is connected, and adjacent to the shaft 55 33 the links 29 and 30 are connected. By means of this connection it will be seen that the fuel pusher 28 and the grate bars 16 are given a somewhat greater movement than the coking plates 15. These coking plates 60 are connected in alternate pairs with the links 29 and 30 so that the plates 43 and 44 are adapted to be operated by the link 30. The links being located on opposite sides of the shaft 33 will be given movement in 65 opposite directions to one another, so that

when the plates 43 and 44 are being tilted to discharge fuel on to the plates 45 and 46, the plates 45 and 46 are being tipped toward plates 43 and 44 to receive the fuel delivered therefrom. When however, the 70 links 29 and 30 receive opposite alternate movement, the plates 43 and 44 are brought to their substantially level positions, while the plates 45 and 46 are being tipped to discharge fuel therefrom, the plate 43 in this 75 position receiving fuel from the distributing plate 27 and the plate 44 receiving the fuel previously contained on the plate 45.

The grate bars 16 like the coking plates 15 are provided with two series of oppositely moving bars, one series 47 being alternately disposed with the other series 48 so that when the series 47 is moving in one direction the series 48 will be moving in the opposite direction. To secure this motion 80 the grate bars are provided with bearing lugs 49 and 50 on their opposite ends, the lugs 49 being adapted to engage the rounded surfaces 51 and 52 of a supporting bar 53 extending transversely of the stoker and journaled in the side members 7 and 8 of the frame 6. As shown in Figs. 1 and 4, the lugs 49 of the series of bars 47, are longer 85 than the lugs 49 on the series of bars 48. This construction permits the upper ends 90 of the bars of both series to be supported at the same level with one another. The bearing lugs 50 are adapted to engage the rounded top edges formed on plates 54 and 55 rotatively mounted on the frame 17 located 95 at the rear of the furnace and extending from one side frame member 18 to the opposite side frame member 19. The support bar 53 is provided on its ends with journal lugs 56 and is adapted to rock upon 100 these lugs so that the rounded surfaces of the bearing lugs 51 and 52 which are 105 equally spaced from the center of the journal lug 56, will have movement in opposite directions when the support bar is oscillated 110 on the lugs 56. Because of this construction the series 47 of the grate bars 16, will have movement in an opposite direction to the grate bar series 48, and the ends of the bars which rest on the plates 54 and 55 will 115 receive motion about the bearing points of the plates 54 and 55 in the frame 17, so that the ends of the bars will reciprocate upwardly and downwardly as well as backwardly and forwardly, as shown in dotted 120 lines in Fig. 1. The purpose of this forward and backward movement is so that the fuel located on the grate will be constantly agitated and urged to move slowly 125 down the inclined grate during its combustion, and so that the clinkers at the lower ends of the bars will be broken up. To secure this rocking movement of the support bar 53, a crank arm 57 is secured to the under face thereof and connected 130

with the link 31 extending from the lower end of the crank arm 42. It will thus be seen that when the link is operated in either direction, the bars of the grate 16 will be given motion in alternate directions.

The movement of the coking plates 43, 44, 45 and 46 with the links 29 and 30 is secured in much the same manner as the movement of the bars of the grate 16, the plates 43 and 44 being provided in this case however, with downwardly extending arms 58 which are connected to the link 29, the arm of the plate 43 having connection with the link 29 by means of a short link 59. The plates 45 and 46 are similarly provided with arms 60 both of which are connected with the link 30, the arm of the plate 45 being connected with the link 30 by means of a short link 61. The reason for providing the links 59 and 61 to connect the arms 58 and 60 of the plates 43 and 45 to the links 29 and 30, is that the points at which the links 59 and 61 are connected to the links 29 and 30, will have movement toward and away from the ends of the arms 58 and 60 when the links 29 and 30 are operated by the double arm crank 42 thus preventing the links 29 and 30 being directly connected to the arms 58 and 60.

Above the fuel pusher 28 the plate 62 is located and a plate 63 located some distance above the plate 62 is provided to form the bottom of the hopper and also to provide means to permit the fuel feeder 26 to reciprocate thereon. Between the plates 62 and 63 openings 64 are provided, these openings constituting stoke holes closed by doors 65 so that the attendant may have access to the interior of the furnace for the purpose of observing the condition of the fuel located on the coking plates and grate bars as well as for observing the distribution of fuel on the distributing plate 27. If the fuel is found to have been improperly distributed on the distributing plate 27 the fuel feeders 26 are adjusted to distribute the coal properly, the means for adjusting the feeders consisting of a screw 66 secured to the feeders and passing through the end of the crank arm 41, the screw being provided with heads 67 at one end and having adjustable nuts 68 located on the opposite side of the crank arms 41 for the purpose of providing some lost motion between the head 67 and the nuts, so that when the nuts are adjusted, the amount of lost motion between the head and the nuts will regulate the amount of movement of the feeders and consequently regulate the amount of coal to be pushed from the plate 63 on to the distributing plate 27.

The means provided for operating the dumping grates 25 consist of bars 69, 70 and 71 which extend from the front to the rear of the furnace and which are con-

nected with arms 72 formed on the under side of each dumping grate section, the dumping grate being formed in sections for convenience of operation. At the forward end of the bars 69 handles 73 are provided and the bars are supported on the transversely extending channel iron member 9, notches 74 being provided in the bars for the purpose of retaining them and the grates connected therewith in their normal position as shown in Fig. 1, when the notches are brought to engage the channel iron member.

In the stoker operating engine which I have illustrated in Fig. 5, I have shown the engine as consisting of a steam cylinder 75 having a piston rod 76 mounted therein and connected with the arm 35 extending from the shaft 34. For the purpose of controlling the engine as to speed and steadiness of operation I have provided an additional cylinder 77 which is provided as is the cylinder 75 with a piston mounted on an extension of the piston rod 76, both ends of the interior of this cylinder being connected by a pipe 78 extending from one end to the other, the cylinder and the pipe being filled with fluid such as oil so that as the piston contained in the cylinder 77 is reciprocated therein the oil will rush through the pipe 78 from one end to the opposite end of the cylinder and thus act to steady the motion of the piston rod. By this means the fuel feeder 26, pusher 28, coking plates 43, 44, 45 and 46, and grate bars 47, 48, will be given a uniform and steady motion.

In operation: Coal is first placed in the hopper 13 and the engine is started so as to cause oscillation of the shafts 32, 33 and 34 through their connected links 37 and 38 and their crank arms 36, 39 and 40. With the shafts in motion the fuel feeder will be given a forward and backward motion corresponding to the amount of movement permitted by the adjustment of the lost motion connection provided between the head 67 of the bolt 66 and the nut 68 mounted thereon. This reciprocation of the fuel feeder 26 will cause a certain amount of fuel to be taken from the bottom of the hopper and to be discharged from the plate 63 from which it will fall onto the distributing plate 27. When a sufficient amount of fuel has accumulated on the distributing plate the fuel pusher 28 which is in constant reciprocation alternating with the reciprocation of the fuel feeder 26, will force a certain amount of fuel over the upturned edge of the distributing plate 27, from whence it will fall onto the coking plate 43. This coking plate is connected with the arm 42^a of the double crank arm 42 in such a manner that it will be rocked to a substantially level position when the fuel pusher 28 is moved forwardly to discharge fuel onto the coking plate.

This permits of the fuel being accumulated on the coking plate 43 until it is tipped to discharge its contents onto the coking plate 45. This last mentioned coking plate being connected by the link 30 to move oppositely to the coking plate 43, will be in its substantially level position to receive the charge of fuel delivered by the coking plate 43, ready for it in turn to be tipped to discharge its contents onto the coking plate 44. This coking plate being connected with the coking plate 43 will operate in the same manner and at the same time as the coking plate 43 so that it will be occupying its level position when the coking plate 45 is occupying its inclined position. The coking plate 44 will therefore receive the contents of the coking plate 45 and when the coking plate 44 is tipped, the coking plate 46 which moves in the same direction and at the same time as the coking plate 45 will receive the contents of the plate 44 so that it in turn may deliver its contents onto the grate bars 47 and 48. This motion of the members 26, 28, 43, 44, 45 and 46 is being carried on continuously so that each time each of the plates is moved they are either receiving or discharging their contents onto other plates or bars. As the fuel is delivered to the grate bars 47, 48 it will by this time have become partially consumed and as the fuel passes over the bars 47 and 48 the consumption thereof will be substantially completed. In order to facilitate this movement of the fuel over the grate bars 47 and 48 the alternate movement of the respective bars has been provided. This movement as above described causes one bar to move in one direction while the bars on each side of it are moving in the opposite direction, not only longitudinally but also vertically at their ends adjacent to the frame 17. At the end of the movement of each bar the movement is reversed. This constant agitation causes the fuel to be gradually worked from the top ends of the grate bars to the lower ends thereof and during such movement the fuel is agitated and turned over a great number of times so as to produce thorough combustion thereof. Should any of the fuel have remained unconsumed at the end of its travel across the grate bars, it will be discharged onto the retarding grate 24 where the combustion will be completed. From this grate the clinkers and remaining ashes of the consumed fuel will be discharged by the fuel passing from the grate bars 47 and 48, onto the dumping grates 25 where the last of the energy to be derived from the fuel is expended. After the accumulation of consumed fuel has been deposited on the dumping grates 25, the handles 73 of the bars 69 are lifted to remove the notches 74 from engagement with the channel iron member 9 and the bars are permitted to

move backwardly to drop the grates 25 for the purpose of discharging the consumed fuel into the ash pit.

Having thus described my invention, what I claim is:

1. In combination in a mechanical stoker, a reciprocally mounted fuel feeder, a distributing plate adapted to receive the fuel delivered by the fuel feeder, a fuel pusher adapted to remove the fuel from the distributing plate, a series of coking plates adapted to receive the fuel delivered from the distributing plate, said plates consisting of a plurality of sets of alternately arranged oppositely moving plates adapted to transfer the fuel delivered from the distributing plate, from one plate to the next adjacent plate, a series of grate bars adapted to receive fuel delivered from the coking plates, said bars consisting of a plurality of sets of oppositely moving alternately arranged bars adapted to maintain agitation of the fuel received from the coking plates, and means adapted to operate the fuel feeder, the fuel pusher, the coking plates, and the grate bars.

2. A mechanical stoker comprising a fuel hopper, a fuel feeder, located at the bottom of the hopper and adapted to discharge fuel therefrom, said fuel feeder consisting of a series of relatively adjustable sections adapted to deliver varying amounts of fuel, a distributing plate adapted to receive the fuel delivered by the fuel feeder, a fuel pusher adapted to remove the fuel from the distributing plate, a series of coking plates adapted to receive the fuel delivered from the distributing plate, said plates consisting of a plurality of sets of alternately arranged oppositely moving plates adapted to transfer the fuel delivered from the distributing plate from one plate to the next adjacent plate, and means adapted to operate the fuel feeder, the fuel pusher, and the coking plates.

3. In a mechanical stoker the combination of a fuel hopper extending transversely of the stoker, a sectional fuel feeder located at the bottom of the hopper and adapted to discharge varying amounts of fuel from the hopper by means of each section, a distributing plate located below the hopper and adapted to receive the varying amounts of fuel delivered from the hopper and to permit of additional distribution of the fuel by gravity during its fall from the hopper to the plate, a fuel pusher located back of the fuel upon the distributing plate, and adapted to push the fuel from the plate, a series of tilting coking plates extending transversely of the stoker and adapted to tilt alternately in opposite directions to and another, said plates being located beneath the distributing plate and successively located beneath each other, adapted to receive the fuel from the

- distributing plate and from each of their preceding superimposed coöperating plates, a series of rearwardly, downwardly and longitudinally extending grate bars located beneath the coking plates and adapted to receive fuel delivered from the coking plates, said grate bars consisting of a series of bars adapted to move in first one direction and then the opposite direction, and a second set of bars adapted to move oppositely to the bars in the first set and alternately arranged therewith, said grate bars being adapted to cause the fuel to move toward their lower ends and to be discharged therefrom, a retard ing grate located beneath the ends of the inclined grate bars and adapted to receive the fuel from the grate bars, and a dumping grate located beneath the retard ing grate and adapted to receive the contents of the retard ing grate, and means adapted to operate the fuel feeder, the fuel pusher, the coking plates, and the grate bars.
4. In a furnace of the character described, the combination of two sets of longitudinal grate bars, the bars of one set alternating with the bars of the other, a transverse member at one end of the grate bars and having two transverse support bars one located above the other and journal pins located between the transverse support bars, one set of grate bars having lugs at one end adapted to engage one of said support bars, the other set of grate bars having lugs adjacent to the lugs of the first set, adapted to engage the other support bar, means for rocking the transverse member about its journal pins and adapted to impart alternating backward and forward movement to the grate bars, and rock plates adapted to support the opposite ends of the grate bars, said rock plates being adapted to carry the plate supported ends of the backwardly moving grate bars at a lower level than the plate supported ends of the forwardly moving grate bars.
5. In combination in a mechanical stoker, two sets of longitudinal grate bars, the bars of one set alternating with the bars of the other set, a transverse member at one end of the grate bars having two support bars, one of said support bars being located above the other, journal pins located in alinement with and midway between the transverse support bars, one set of grate bars having lugs at one end adapted to engage one of said support bars, the other set of grate bars having lugs adjacent to the lugs of the first set adapted to engage the other bar, means for rocking the transverse member about its journal pins and adapted to impart alternating backward and forward movement to the grate bars, and rock plates adapted to support the opposite ends of the grate bars, said rock plates being adapted to carry the plate supported ends of the backwardly moving grate bars at a lower level than the plate supported ends of the forwardly moving grate bars.
- In testimony whereof, I have hereunto subscribed my name this 1 day of May, 1915.
- JENKIN P. DAVIS.
